UNITED STATES PATENT OFFICE.

TIMOTHY HOLLAND, OF TROY, NEW YORK.

LUBRICATOR.

SPECIFICATION forming part of Letters Patent No. 290,685, dated December 25, 1883.

Application filed June 8, 1883. (No model.)

To all whom it may concern:

Be it known that I, TIMOTHY HOLLAND, of the city of Troy, county of Rensselaer, and State of New York, have invented a new and 5 useful Improvement in Lubricators, of which the following is a specification.

My invention relates to that class of devices used to distribute oil to the working parts of machinery, termed "lubricators," and my invention more particularly consists, as will hereinafter be more fully described, in certain improvements upon the well-known lubricator patented to J. Absterdam, November 21, 1854, and in which device oil was arranged to 15 drop from a pendent nozzle in a visible form into a conduit-pipe, which conveyed it to the point of application, the oil so distributed being floated up to the point of discharge to fall in visible drops by the water in the cup beneath the oil, and with the cup connected with 20 the boiler for water supply and pressure.

In the accompanying drawings, forming a part of this specification, there are four figures shown illustrating my invention, and in 25 all of which the same designation of parts by letter-reference is used.

Figure 1 shows a vertical section taken centrally through a lubricator containing my invention and improvement. Fig. 2 illustrates 30 a cross vertical section, taken on the line x^2 of Fig. 1, one of the pendent nozzles, of which there are two in the device, each being the oppositely-arranged counterpart of the other, with said section showing also the connection of the horizontal extension of the oil-overflow pipes and the nozzles, illustrating 35 also the position of the valve-stem which regulates the supply of oil to the pendent nozzles. Fig. 3 shows a horizontal section of the parts, 40 taken on the line $x'x'$ of Fig. 1, in an enlarged proportion, to better illustrate the details. Fig. 4 illustrates a modification of the sight-opening applied to each of the two opposite sides of the lubricator, through which to see 45 the descending drops of oil, and in which modification there is shown a single pane of glass, used at the front and rear of the lubricator, made large enough to open a view of both pendent nozzles, instead of two sight- 50 openings, at the front and rear, being con-

structed with one pane opposite each of the two nozzles at the front and rear.

The several parts of the lubricator and those constituting my invention are designated by letter-reference and their construction described as follows:

The letter L indicates a chamber for containing oil and water, the position of the oil being designated at O, and the water at W.

The letters $a a$ indicate two pipes, into which the oil is floated by means of the water beneath it in the chamber L.

The letter C designates an upper inclosure, divided in two parts by a partition, P, extending from front to rear, the parts of the upper chamber thus divided off by the said partition being indicated at d d. The oil-pipes $a a$ are constructed to pass upwardly through this partition, and to each turn out laterally and oppositely, to connect with the pendent nozzles N N, each of which opens downwardly into one of the chambers d d.

The letter V² indicates a plug-valve arranged on each one of the lateral extensions of said oil-pipes $a a$, by means of which the amount 75 of oil floated up into said pipes to be discharged from said nozzles may be regulated.

The letter S' designates a steam-pipe connected with the boiler, and intermediately provided with a valve, V', to regulate the 80 amount of pressure entering the lubricator through the pipe S'. This steam-pipe opens into the annular cored-out space m, and the latter communicates with the chambers d d, to communicate pressure thereto. The letter S² indicates another steam-pipe, which, at its upper end, is placed within the steam-pipe S', being smaller than the latter, and with its upper end opening into said pipe S'. The pipe S² extends downwardly through the partition P, as shown at Figs. 1 and 3, to near the bottom of the chamber L. This steam-pipe S² conveys steam and the water produced by its condensation into the said chamber L. Thus combined and arranged, the chambers d d and L are under the same pressure, and the water which collects in the chamber L serves to float the oil contained therein, so as to raise it up into and through the lateral extensions of the pipes $a a$ to the pendent nozzles N N, from 90 95 100

which it falls into the chambers *d d*, from whence it passes by means of the openings *E* to conduit-pipes, to be conveyed to the point of application.

5 At *A' A'*, Fig. 1, there are indicated two glass panes, and at Fig. 3 the two panes placed oppositely and at the back of the lubricator are shown. These panes of glass constitute openings through which the downward passage of the oil may be seen.

At *A²*, Fig. 4, there is shown a single pane of glass made large enough to take in a view of both nozzles, and when used in this form it is applied to a corresponding opening made in 15 the lubricator at the front, with one of like construction attached oppositely at the back of the device.

The letter *F* indicates the frame in which the glass is secured for attachment, and this 20 frame may be connected to the edge of an opening formed therein by means of screws with packing, or by any other known means that will make a steam-tight joint. The smaller panes *A'* are packed in rings when used in 25 place of the large panes, and the rings are threaded to screw into corresponding openings made in the lubricator; or they may be attached in any known manner by which a steam-tight connection may be produced.

30 The panes used in either way have but one function—that of producing a means by which the descent of the oil may be seen.

The letter *p* indicates a pipe connecting with the chamber *L* at *n*; *V*, a valve for 35 closing such opening and pipe, and *C* a cup connecting with the pipe for supplying oil to the lower chamber, *L*.

The letter *D* designates a drip-cock for relieving the chamber *L* of an excess of water.

40 In the older Absterdam patent alluded to, but one pendent nozzle was used, from which the oil dripped into the open end of a conduit-pipe. In my device two nozzles are used, each of which opens into a separate chamber, 45 wherein the oil drips, and each of the chambers is provided with a conduit-pipe, to convey the oil to the point of application, while the pipes that supply the nozzles are each provided with valves to regulate the amount 50 of oil delivered to each nozzle, so that quantitatively each nozzle operates independently of the other; hence my device is not a mere duplication of the Absterdam pendent nozzle. Where glass tubes are used in lubricators, as an offset made from the body thereof, in connection with laterally-extended pipes, the apparatus necessarily takes up a good deal of space, and when applied to locomotives this feature of their construction is ob- 55 jectionable. Thus made, they are liable to be broken, and such construction adds to their cost. When by my improvement the transparent part of the apparatus, and that by which the proper flow of the oil may be de- 60 termined, is made a part of the body proper

without any offset construction on the device, the latter takes up much less room, is less liable to be broken from its compactness, and the cost of its production is much reduced.

Having thus described my invention, what 70 I claim, and desire to secure by Letters Patent, is—

1. In a lubricator, the combination of an upper oil-distributing chamber divided in two parts, a pendent oil-delivery nozzle for each 75 part of the chamber, and outlets from each of the divided parts of the chamber, adapted to connect with conduit-pipes, as and for the purposes herein set forth.

2. In a lubricator, the combination of an 80 upper chamber constructed in two parts by means of a partition extending from front to rear, panes of glass in the wall of the chamber, arranged oppositely at the front and rear of the divided parts of said upper chamber, 85 a pendent oil-delivery nozzle for each part of said divided chamber, and an opening in each part of said chamber, to attach an oil conduit-pipe, as herein shown and described.

3. In a lubricator, the combination of an 90 upper chamber constructed in two parts by means of a partition extending from front to rear, panes of glass in the exterior wall of the chamber, arranged oppositely at the front and rear of the divided-off parts of said chamber, 95 a pendent oil-delivery nozzle for each part of said chamber, an oil-supply pipe and valve connecting each of said nozzles with the oil and water chamber of the lubricator, and an opening in each of the divided-off parts of 100 said upper chamber, for the attachment of an oil conduit-pipe, as herein shown and described.

4. In a lubricator, the combination of a bottom chamber constructed with an oil-intake, 105 and a connection with the steam-boiler to receive steam, water, and pressure therefrom, an upper oil-distributing chamber divided from front to rear in two parts, and each of said parts constructed to receive steam-pressure from the boiler, panes of glass in the 110 walls of the upper chamber, arranged oppositely therein at the front and rear thereof, a pendent oil-delivery nozzle in each divided-off part of said upper chamber, a pipe having a valve thereon, connecting each of the oil-delivery nozzles with the oil and water chamber in the bottom of the lubricator, and an opening in each divided-off part of the upper chamber, for the attachment of an oil conduit-pipe, as herein shown and described. 115

5. In a lubricator, the combination of an upper oil-distributing chamber divided in two parts by a partition extending from front to rear, a pendent oil-delivery nozzle in each 125 divided part of said upper chamber, an outlet from each divided-off part of the chamber, for attaching an oil conduit-pipe, an oil-supply pipe for each of said nozzles, and an annular passage-way around said pipes, con- 130

necting with each of the divided parts of said chamber and with the inlet-pipe, which supplies steam from the boiler to the lubricator, as and for the purposes described and set forth.

5. In a lubricator, the combination of the upper chambers, $d\bar{d}$, the annular opening and passage-way m , the steam-pipes S' and S^2 ,

and the lower chamber, L , arranged and constructed to operate as herein shown and described.

TIMOTHY HOLLAND.
